[57] CLAIM

The ornamental design for hanger for hoses and attachments, as shown.

DESCRIPTION

FIG. 1 is a perspective view of a hanger for hoses and attachments, with broken lines shown for illustrative purposes, showing my new design;

FIG. 2 is a top view thereof;

FIG. 3 is a front view thereof;

FIG. 4 is a right side elevational view, the left side being a mirror image thereof;

FIG. 5 is a rear elevational view thereof; and

FIG. 6 is a bottom view thereof.

FIG. 2

FIG. 1

FIG. 3

FIG. 4

FIG. 5

FIG. 6
